UNITED STATES PATENT OFFICE.

JOHN SCHUSTER, OF CLAY BANKS, WISCONSIN.

WAGON-RACK.

No. 638,658.

Specification of Letters Patent.

Patented Dec. 18, 1906.

Application filed January 31, 1906. Serial No. 298,856.

To all whom it may concern:

Be it known that I, JOHN SCHUSTER, a citizen of the United States, residing at Clay Banks, in the county of Door and State of Wisconsin, have invented a new and useful 5 Wagon-Rack, of which the following is a specification.

This invention relates to wagon-racks; and its object are to provide a rack of simple 10 and improved construction which may be easily and conveniently applied to a wagon-box of ordinary construction for the purpose of converting the latter into a cage or coop for the transportation of live stock or poultry 15 for the purpose of enabling a large load of material to be conveniently carried upon the wagon.

With these and other ends in view, which will readily appear as the nature of the invention is better understood, the same consists in the improved construction and novel arrangement and combination of parts, which will be hereinafter fully described, and particularly pointed out in the claims.

25 In the accompanying drawings has been illustrated a simple and preferred form of the invention, it being, however, understood that no limitation is necessarily made to the precise structural details therein exhibited, 30 but that changes, alterations, and modifications within the scope of the invention may be made when desired.

In the drawings, Figure 1 is a side elevation showing a wagon-box equipped with a 35 short rack constructed in accordance with the principles of the invention. Fig. 2 is a side elevation showing a wagon-box equipped with a long rack constructed according to the invention. Fig. 3 is a vertical transverse 40 sectional view taken on the plane indicated by the line 3-3 in Fig. 1. Fig. 4 is a perspective view showing the top of the rack, together with the end gate, detached. Fig. 5 is a perspective detail view of one of the 45 sides of the rack seen from the inside. Fig. 6 is a transverse sectional view of a wagon- 50 box equipped with the side racks and showing a partition being placed in position. Fig. 7 is a perspective view illustrating a modification.

Corresponding parts in the several figures are indicated throughout by similar characters of reference.

The improved rack belongs to that class 55 which may be knocked down and assembled and which may be arranged in various ways

so as to serve for various purposes. In the construction of the rack there are included a plurality of uprights or standards 1-1, preferably constructed of wood and of suitable 60 dimensions to insure the necessary strength and rigidity. The stakes or uprights 1-1 are provided at their lower ends with flat metallic hook members 2, having upturned terminal lips 3. Each of said uprights is also 65 provided with a plurality of apertures, as 4, for the reception of hook-bolts 5, having nuts 6.

The hook members 2 of the standards are adapted to catch underneath the bottom 6-6 of a wagon box or bed 7, recesses, as 8, being provided for the reception of the links 3. The lowermost hook-bolt 5 is adapted to catch over the upper edge of the side member 9 of the wagon-box, so that the upright may be 75 very firmly secured in position by merely tightening the nut upon said hook-bolt. The remaining hook-bolts 5 of the uprights, two or more of which are mounted upon each side of the wagon-box, are disposed in pairs 80 for the purpose of holding in position planks 10-10, which coöperate with the uprights to constitute the sides of the rack. These planks may be of any desired length. To construct a short coop or cage for the transportation of poultry, sheep, or other small animals, relatively short planks may be used, and two stakes or uprights upon each side of the wagon-box will be sufficient to support the planks. When it is desired to 90 construct a long capacious rack for the transportation of live stock or for the purpose of increasing the capacity of the wagon-box for the transportation of hay, grain, garden truck, and the like, it is desirable to use 95 three or more stakes upon each side of the wagon-box, and long planks of any desired length may then be used, as shown in Fig. 2 of the drawings, or the planks may be of shorter length, and they may be overlapped, 100 as will be seen in Fig. 7 of the drawings. By connecting the planks with the uprights or standards 1-1 by means of hook-bolts, as herein described, the planks may be readily interchanged when desired, and the sides of 105 the rack may be built up in various ways, which will readily suggest themselves to the user of the device.

When the device is to be utilized as a coop for the transportation of poultry or small stock, a top member 11 is used, said top member being composed of a plurality of

planks 12 12, nailed or otherwise secured upon the cross bars or braces 13, supported upon the planks 10. Rods 15 are provided upon which end gates, as 16, are hingedly mounted, said end gates being composed of planks 17, suitably secured upon vertical braces 18, the upper ends of which are perforated for the passage of the hinge-rod 15. The upper ends of the uprights 1 are provided with notches 19 for the reception of the hinge-rod, thus enabling the top members and the end gates to be easily and quickly placed in position or removed from the side racks, as may be desired, without necessity of removing the hinge-rods. The end gates are provided with cross-bars 20, secured upon the vertical bars 18 and provided with hook-bolts 21, adapted to engage the uprights 1, with which the end gate is hingedly connected; so as to secure the end gate in locked position. By using an end gate, as 16, at each end of the rack or structure and by using a top member of suitable length a coop or cage of proper dimensions may be readily constructed in which poultry or small stock may be confined for transportation.

If desired, one or more horizontal partitions, as 22, may be used, as will be understood by reference to Fig. 6 of the drawings, thus increasing the capacity of the coop by subdividing it horizontally.

Access to any compartment of the coop may be readily had without opening the end gates by simply loosening the bolts, in the uprights 1 at one side of the structure sufficiently to enable one of the side planks 10 to be partly slipped aside, as will be clearly seen by reference to Fig. 5 of the drawings, it being understood that the end gates are of such a width as to fit between the sides of the rack.

From the foregoing description, taken in connection with the drawings hereto annexed, the operation and advantages of this invention will be readily understood by those skilled in the art to which it appertains.

A rack embodying the improvements may be readily constructed at a very moderate expense, and it is capable of being used in a great variety of ways and for a great variety of purposes, which will readily suggest themselves.

Having thus described the invention, what is claimed is—

1. In a wagon-rack, a plurality of uprights

having wagon-box-engaging hooks provided with terminal upturned lips, wagon-box-engaging hook-bolts extending transversely through said uprights, plank-supporting hook-bolts extending transversely through the uprights, and planks supported by said hook-bolts.

2. The combination with a wagon-box 65 having side members and a bottom provided with recesses near the edges thereof, of uprights or standards having hook members provided with upturned terminal lips adapted to engage the recesses in the bottom member of the wagon-box, hook-bolts extending transversely through the uprights and engaging the upper edges of the side members of the wagon-box, additional pairs of hook-bolts extending through the uprights, and 75 planks supported adjustably and detachably by said hook-bolts and co-operating with the uprights to constitute the side members of a rack.

3. In a wagon-rack, side members including uprights having box-engaging hooks at their lower ends and box-engaging eyebolts, and longitudinally-disposed planks connecting and supported by the uprights; in combination with a horizontal partition insertible between the side members and capable of being supported upon the longitudinal planks of the latter.

4. The combination with a wagon-box of uprights having notched upper ends and provided with box-engaging hooks having upturned terminal lips, hook-bolts extending through the uprights and engaging the upper edges of the side members of a wagon-box, additional pairs of hook-bolts extending 95 through the uprights, planks supported adjustably and detachably by said hook-bolts, top members having cross-bars supported upon the planks, transverse rods engaging the notches at the upper ends of the uprights, end-gates having vertical bars hinged upon said rods, transverse bars secured upon the vertical bars, and hook-bolts extending through the transverse bars and adapted to engage the uprights or standards to secure 105 the end-gates in position.

In testimony that I claim the foregoing as my own I have hereto affixed my signature in the presence of two witnesses.

JOHN SCHUSTER.
